United States Patent Office

Des. 220,369
Patented Mar. 30, 1971

220,369

PACKAGING MATERIAL

John E. Stengel, Chesterfield County, Va., assignor to
Reynolds Metals Company, Richmond, Va.

Filed Apr. 25, 1969, Ser. No. 16,895

Term of patent 14 years

Int. Cl. D5—03

U.S. Cl. D59—2

The figure is a plan view of a packaging material showing my new design, the design unit shown enclosed with broken lines being repeated in regular succession beyond the unit boundaries.

I claim:

The ornamental design for a packaging material, substantially as shown and described.
